UNITED STATES PATENT OFFICE

2,486,711

SHIPPING CONTAINER

Alexander Harris, Scobeyville, N. J., assignor to
 Ronson Art Metal Works, Inc., Newark, N. J., a
 corporation of New Jersey

Application March 19, 1946, Serial No. 655,529

1 Claim. (Cl. 206—46)

1

The invention aims to provide a shipping or storing container for cigar lighters or the like which will enable the lighters to be safely shipped and stored while charged with inflammable lighter fluid, and without substantial loss of fluid while so stored, the lighters being also adequately protected against injury while stored in the container. Further objects and advantages of the invention will be in part obvious and in part specifically referred to in the description herein-after contained which taken in conjunction with the accompanying drawings discloses a preferred form of shipping container which is constructed to operate in accordance with the invention.

In the drawings:

Fig. 1 is a plan view of a container constructed in accordance with the invention;

Fig. 2 is a central vertical section taken on line 2—2 of Fig. 1 looking in the direction of the arrows and with the lighter shown in stored position in the container; and

Fig. 3 is a section on line 3—3 of Fig. 2 looking in the direction of the arrows.

The invention is disclosed as embodied in a shipping container which is provided with a casing or housing having side walls 1 which loosely surround the lighter to be stored, and a bottom wall 2 which supports the base of the lighter. The top wall 3 of the casing is provided with a charging opening 4 which admits the lighter to be stored, the construction of the casing being otherwise fluid-tight.

The lighter may be understood as having a fuel receptacle 5 which receives volatile and inflammable lighter fluid, a base 6, and a top portion comprising a finger piece 7 and a snuffer 8. This type of lighter is well known in the art and accordingly need not be described in greater detail.

A detachable cover member 9 is in substantially fluid-tight engagement with the wall portions 3a (Fig. 2) of the top wall 3 of the casing, which wall portions 3a surround the charging opening 4. In the illustrated form of the invention the cover 9 is provided with a flange 10 which has a press fit against the wall portions 3a, to effect a substantially fluid-tight seal and yet enable the cover to be readily pried off when desired.

The lighter is held against shucking within the container, and in spaced relation to the side walls 1, by engagement between the cover 9 and the opposed bottom wall 2 of the casing. As shown, the bottom wall 2 is provided with a pocket or recess 11 which is complementary in shape to the base 6 of the lighter, the surrounding walls 12 of such pocket holding the base of the lighter firmly in stored position. Preferably a resilient pad 13 of packing material, which may be constructed of fibrous padding, sponge rubber or the like, is interposed between the base 6 of the lighter and the walls of pocket 11. Also the cover 9 of the container is shown as provided with a

similar pocket or recess 14 which is complementary in shape to the top members 7 and 8 of the lighter, so as to hold the top of the lighter firmly in stored position in like manner. A pad 15 of packing material, similar to the pad 13 above described, also is preferably interposed between the top of the lighter and the adjacent parts of the cover.

A container of the above character enables the lighter to be safely shipped or stored while charged with volatile and inflammable lighter fluid such as is customarily used in lighters of the pyrophoric type. Evaporation of the lighter fluid is minimized, the container being substantially fluid-tight, and the lighter is held firmly in stored position, in spaced relation to the exterior portions of the container, in such manner that it is not likely to be damaged during shipment.

While the invention has been carried out by a container of the above described specific construction, it should be understood that changes may be made therein without departing from the invention in its broader aspects, within the scope of the appended claim.

I claim:

A shipping container for lighters and the like including a metallic casing having unitary side walls constructed to loosely surround the article to be stored, and having upper and lower edges positioned respectively above and below said article, a top wall constructed to overlie the article to be stored, said top wall being tightly fastened to the aforesaid upper edges, said top wall having an opening therethrough of smaller cross section than the space within said side walls, the said casing having a bottom wall tightly fastened to the said bottom edges and also having an interior pocket constructed to position the base of the article to be stored, said casing also having a cover member tightly but releasably engageable with the walls of said opening in the top member, said cover being movable downwardly into a position wherein it presses said article toward the aforesaid pocket, said cover also having an interior pocket therein, and opposed pads of compressible material seated respectively in the aforesaid pockets, which pads are constructed to hold the article to be packed between them.

ALEXANDER HARRIS.
